CLAIM

The ornamental design for a bag clip, as shown and described.

DESCRIPTION

FIG. 1 is a perspective view of the bag clip in an open position showing my new design;

FIG. 2 is a bottom view thereof;

FIG. 3 is a top view thereof;

FIG. 4 is left side view thereof;

FIG. 5 is a right side view thereof;

FIG. 6 is a front view thereof; and,

FIG. 7 is a rear view thereof.

The broken lines illustrate environment structure that forms no part of the claimed subject matter.
